UNITED STATES PATENT OFFICE

WILLIAM AITKEN, OF LONDON, ENGLAND, ASSIGNOR, BY MESNE ASSIGNMENTS, TO AUTOMATIC ELECTRIC INC., OF CHICAGO, ILLINOIS, A CORPORATION OF DELAWARE

GRADED FINDER SYSTEM

Application filed May 21, 1925, Serial No. 31,808, and in Great Britain August 21, 1924. Renewed September 29, 1928.

The present invention relates to telephone systems employing automatic switches and is more particularly concerned with systems employing switches of the backwardly hunting or finder type. As is well known, the function performed by these switches is essentially similar to that of line-switches of the forwardly hunting type, but the controlling arrangements must of course be different and in general the quantities involved will be different also. When the switches are used for connecting a calling subscriber's line with a first numerical switch, if line-switches are used, they must be provided individual to each calling line and hence a large number are required. These switches, however, are comparatively cheap and simple to manufacture and further, the selector switches to which the line-switches have access may be arranged in comparatively large groups, for instance groups of 25, so that the number of expensive selector switches is reduced to a minimum. With finder-switches on the other hand, if they are arranged to be of large capacity, a special switch construction is necessary if unduly long hunting time is to be avoided, while if they are standard switches of small capacity, not only must a much larger number be employed, but since each finder-switch is usually directly linked to a selector switch, the expensive selector switches must also be provided in greater quantity.

The object of the present invention is to overcome this drawback to the use of finder-switches and to enable a small type of finder-switch similar in construction to a line switch to be employed without unduly increasing the number of numerical switches to which the finder-switches are linked.

According to the invention, in a system employing finder-switches which hunt for lines arranged in groups corresponding to the capacity of each finder-switch, some of the finder-switches are connected to individual terminals of the succeeding switching devices, while others are connected in multiple to the terminals of the succeeding switching device.

According to another feature of the inven-

tion, in a system employing backwardly hunting switches for connecting subscribers' lines to numerical switches, the numerical switches are arranged to be taken into use in a definite order of priority, in which order the switches are accessible from successively larger groups of subscribers' lines.

A further feature of the invention is that in a system employing finder switches for connecting a calling subscriber's line to a first numerical switch, the finders are adapted to be taken into use in a definite order of priority, the finders adapted to be first taken into use for connecting with a calling line being linked to individual switching devices, while those taken into use when all of the first class are busy are connected in successively larger groups to switching devices common to more than one finder.

The invention will be better understood from the following description of a preferred embodiment taken in conjunction with the accompanying drawings. It will be understood that though the form described concerns the novel arrangements of finders for connecting subscribers' lines to numerical switches, the invention is not limited to such use nor to the exact circuit arrangements shown.

Referring now to the drawings, Fig. 1 shows various arrangements of finders which are possible according to the invention; in illustrations A and B 25 point finders are used, and in illustration C 50 point finders are used. D and C respectively show two arrangements of what may be termed "grading" in the banks of the finder alloters associated with the various groups.

Fig. 2 is a circuit diagram showing the actual connections when finders of two different groups are connected in multiple to a common succeeding switch, while Fig. 3 shows the wiring of the finder allotter banks.

In illustration A there are shown two groups of subscribers' lines *a* and *b*, each group comprising 25 lines which are served by five finder-switches. In each group it is arranged that by means of an allotter (not shown) the finder-switches are taken into use in a definite order of priority, for instance the trunk lines associated with the finders in

100

group *a* will be taken into use in the order 1, 2, 5, 6, 7. Thus when the traffic is light it may all be carried by lines 1 and 2 which are individual to the group *a*, while similar conditions in group *b* are taken care of by lines 3 and 4. The lines 5, 6 and 7, however, are common to the two groups, but are only taken into use when the individual lines in the group are already busy. It will be appreciated that the principle involved is the same as that employed in grading as applied to forwardly hunting switches.

Illustration B shows a possible arrangement with three groups of subscriber's lines *c*, *d* and *e*, with a somewhat heavier traffic, so that each group is served by six finder switches. In this case the first two trunks 8 and 9, 10 and 11, 12 and 13, for each group are individuals, the next two in each group, 14, 15 and 18 are common to two groups, while the last two 16 and 17 are common to all three groups. By this arrangement a total of 11 trunks is made to serve for the three groups as against 18 if each group had all its six trunks individual.

In illustration C the numbers are slightly different, but the principle remains the same. In this case there are two groups of subscribers' lines *f* and *g* and each comprises 50 lines. Under these circumstances 9 finders are provided to deal with the traffic of each group and the first five trunks 19-23 and 24-28 are individual, and the last four 29-32 are common, so that a total of 14 suffices.

The illustrations D and E show in a different manner the grouping arrangement. These illustrations represent the bank contacts of the finder allotters, one of which is associated with each group. In D it is assumed that there are four groups and hence four allotters and that six finders are provided to take care of the traffic in each group, and moreover that the home position of each allotter is at the bottom of each vertical row of contacts. It will be seen then that the first two contacts are connected to individual finder links, the third and fourth contacts are connected to links which are common to two groups, though the grouping is different in the two cases, while the fifth and sixth positions lead to finders which are common to all four groups. In illustration E, four groups are again assumed and seven finders, and in this case the connection of the finders in pairs is further mixed on the fourth contacts.

Fig. 2 shows detailed circuits for the case in which two finders are connected together to a common succeeding switch for instance a first selector. The circuits would not however need alteration if a larger number of finders were employed in multiple, the connections of the additional switches being readily apparent to those versed in the art. The finder-switches represented by FS and FS' are mechanically identical with line-

switches of well known type, with wipers having no normal position and moving always in the same direction and having either 25 or 50 contacts. A suitable number of these switches are provided for each group of lines and the order in which these switches are taken into use is determined by a finder allotter such as FA. This switch is mechanically identical with any of the finders except that it is provided with a normal position to which it returns when not actually in use.

The leads 1 and 2 extend to a substation and incoming connections for this station are completed from a connector over the leads 3, 4 and 5. The combined line and cut off relay 6 is arranged to operate in two stages according as to whether it is energized over its top or bottom winding.

Suppose now that the subscriber under consideration initiates a call. When he removes his receiver, a circuit is completed as follows: battery, both windings of common start relay 7, lower winding of line relay 6 of the calling line, back contact and armature 11, conductor 1, subscriber's loop, conductor 2, armature 12 and its back contact, earth. Owing to the high resistance of this circuit, relay 6 does not operate but relay 7 operates and at armature 8 short circuits its high resistance lower winding. Relay 6 then receives enough current for it to operate its armature 10 only, whereby the calling line is placed in condition to be found by the finder-switch allotter. The operation of armature 8 also completes a circuit for relay 13, which thereupon energizes and applies earth at armature 14 to the test contacts associated with all the lines in the group except those actually in use.

Moreover, at armature 9 relay 7 completes a circuit as follows: earth, armature 9 and its front contact, normal contact 17 in the bank of the allotter FA, homing wiper 18, back contact and armature 15, winding of series relay 19, interrupter contact and magnet 20 to battery. The wipers of the finder allotters are thus advanced one step before the above circuit is opened at armature 15. The control of the hunting operation is then transferred to the test wiper 21 and this operation continues until wiper 21 engages a contact, for instance the contact 22 to which earth is not connected. At armature 16 a circuit is prepared for line relay 23 of the allotter, this circuit not being operative for the present owing to the fact that it is open at armature 24 of series relay 19 as long as the allotter is hunting to find an idle finder.

Assuming that the finder FS is the one taken into use, relay 19 de-energizes when the allotter FA comes to rest and completes a circuit for relay 23 which thereupon energizes and at armature 25 completes a circuit for switching relay 27 of the finder allotter and stepping magnet 28 of the finder

FS, in series, and at armature 26 connects test wiper 29 to the junction of relay 27 and magnet 28. Since all the lines of the group except the calling line have earth connected to their test contacts, unless the wipers of FS are already standing on this line relay 27 is short-circuited and magnet 28 is energized and de-energized to step the wipers round until the calling line is found. When this occurs, relay 27 is no longer short-circuited and energizes, thereby at its armature 30 completing a circuit for connecting relay 31. Relay 31 upon energizing, at armatures 32 and 33 connects the speaking leads through, at armature 34 connects earth to test wiper 29 and at armature 35 prepares a locking circuit for itself. The connection of earth to wiper 29 completes a circuit for the upper winding of line relay 6 which thereupon energizes fully and at armatures 11 and 12 disconnects conductors 1 and 2 from its lower winding and earth respectively. The circuit of relay 7 is thereby opened and unless other calls have been initiated in the meantime, it commences to de-energize. Upon the operation of armature 35, the following circuit is completed: earth, armature 30 and its front contact, wiper 36' and the contact on which it is resting, front contact and armature 35, contact 22, wiper 21, front contact and armature 15, series relay 19, stepping magnet 20 to battery. The finder allotter FA is thus advanced one step and by the operation of series relay 19 the circuit of relay 23 is opened so that it de-energizes and opens the circuit of relay 27. Unless any other calls are waiting attention relay 7 now de-energizes and opens the circuit of relay 13 which de-energizes also. A circuit for restoring the finder allotter to normal is then completed as follows: earthed multiple contacts 36, wiper 18, back contact and armature 15, relay 19, magnet 20 to battery. Since this circuit is completed intermittently under the control of the interrupter contact until wiper 18 engages contact 17 which is now dead, the switch is restored to normal in readiness to complete other connections.

During the conversation the relays 6 and 31 are held up by earth fed back on release trunk conductor 37 from one of the numerical switches. When the calling party hangs up his receiver this earth is removed and relays 6 and 31 de-energize and the link is freed. It may then be used to establish a connection by way of the finder FS' since when earth is removed from conductor 37, FS' will no longer test busy in the bank of the finder allotter FA'.

One important feature of the arrangement shown should be noted, namely that the finder allotter is stepped on after the calling line has been found irrespective of whether earth is fed back from the numerical switch. In the ordinary course, this earth will be sent

back before the earth at armature 30 has been removed, but in case the trunk associated with the selected finder should be faulty, earth will not come back and relay 31 will de-energize. The removal of earth from test wiper 29 partially de-energizes relay 6, so that the circuit of relay 7 is again completed and since it is slow it will not have released during this interval. Hence the finder allotter FA will again hunt for an idle finder, and this will then operate to find the calling line and the connection will be completed thereover.

The operation when a connection is extended from the group served by the finders such as FS' is precisely similar and it will be seen that as soon as the link has been taken into use by either FA or FA', it is impossible for it to be seized over the other path. Moreover it is not possible for more than one connecting relay to be operated at once since the initial energizing circuit is completed from the finder allotter.

Fig. 3 depicts the bank wiring of the finder allotters FA and FA', only the banks engaged by the wipers 18 and 21 being shown. The switches are shown as having 25 points and a total of 18 trunks are provided of which 7 are individual to each switch and the remaining four are common. Since the number available to each switch is only 11, they are multiplied twice round the bank so as to avoid the necessity of an excessive movement on returning to normal, there being thus two normal positions. The lead 38 in Fig. 3 extends to the contact such as 9 of the common start relay.

Thus by means of the invention one of the most serious disadvantages of small capacity finder switches has been overcome. It will be understood, however, that the invention is equally applicable to large capacity finders though, as pointed out above, the greatest advantages of the arrangement are to be found in connection with finders of small capacity.

What is claimed is:

1. In a trunking system of a telephone system, a group of line finder switches divided into sub-groups, subscriber controlled numerical switches for extending connections, a certain number of said last switches being allotted individually to a corresponding number of finder switches comprising one sub-group, and another number of said switches each of which is connected in common relation with a plurality of finder switches of another sub-group.

2. In a trunking system of a telephone system, a group of line finder switches divided into sub-groups, subscriber controlled numerical switches for extending connections, a certain number of said last switches being allotted individually to a corresponding number of finder switches comprising one sub-group, another number of said switches each

- of which is connected with a plurality of finder switches of another sub-group, and a third number of said switches each of which is connected in common relation with a 5 greater plurality of finder switches of a third sub-group than in the second.
3. In a trunking system of a telephone system, a group of line finder switches divided into sub-groups, subscriber controlled numerical switches for extending connections, a certain number of said last switches being allotted individually to a corresponding number of finder switches comprising one sub-group, another number of said switches each 10 of which is connected with a plurality of finder switches of another sub-group, and means for causing the said numerical switches to be allotted for use by calling lines in a definite order of priority in which order the 15 switches are accessible from successively larger groups of subscribers' lines.
4. In a trunking system of a telephone system, a group of line finder switches divided into sub-groups, subscriber controlled numerical switches for extending connections, a certain number of said last switches being allotted individually to a corresponding number of finder switches comprising one sub-group, another number of said switches each 20 of which is connected with a plurality of finder switches of another sub-group, and means for causing the finder switches and the numerical switches to be used in a definite order of priority.
5. In a telephone system, finder switches for connecting a calling subscriber's line to one of a group of first numerical switches, means for causing the finders to be taken for use in a definite order of priority, the finders first taken for use being linked to numerical switches individual to them while a number 25 of those taken into use thereafter are connected in common to another numerical switch.
6. In a telephone system, groups of subscribers' lines, some of said groups being larger than others of said groups, numerical switches, backwardly hunting switches for connecting subscribers' lines to said numerical switches, and means for causing said numerical switches to be taken for use in a definite order of priority, in which order some of said numerical switches are accessible from successively larger groups of subscribers' lines than other of said numerical switches.
7. In a telephone system, finder switches arranged in groups, a group of other switches, means for connecting certain of said finder switches to individual ones of said other switches, and means for connecting others of said finders in multiple to the other switches.
8. In a telephone system, a calling line, a plurality of finder switches having access to said line, other finder switches, a plurality 65 of numerical switches for extending connections to called lines, certain of said numerical switches being individual to certain of the finder switches while others are directly connected without intervening switches to a 70 number of the finder switches, and means for causing the first of the numerical switches to be taken for use ahead of those which are common to a number of the finders.
9. In a telephone system employing backwardly hunting switches for connecting subscribers' lines to numerical switches, means including an allotting switch for causing the numerical switches to be taken into use in a definite order of priority, and means for causing the said allotter to be moved to a distinctive position at any time no finder under its control is performing a hunting operation. 75
10. In a telephone system, numerical switches for extending connections, backwardly hunting switches for connecting the numerical switches to subscribers' lines, means including an allotting switch for causing the finders and numerical switches to be taken into use in a definite order of priority, and finder controlled means for completing a 80 circuit for advancing the allotter responsive to the finder's coming to rest on a calling line.
11. In a telephone system, groups of calling lines, a corresponding number of groups of trunks, means for enabling the lines of one group to extend connections only via a particular group of trunks and for enabling the lines of more than one group to extend 85 connections via a trunk of another of said groups.
12. In a telephone system, a calling line equipped with a combined line and cut off relay, a finder switch having access to said line, a second relay, a circuit including said first and second relays completed responsive to the initiation of a call for operating said second relay, means operated by said second relay for partially operating said first relay to thereby distinguish the calling line from others to which the finders have access, and said second relay at the same time causing the first relay to become fully operated by causing a preselected finder to find the calling line. 90
13. In a telephone system, groups of subscribers' lines of various sizes, numerical switches, and means for causing said numerical switches to be taken for use in a definite order of priority, in which order some of said switches are accessible from successively larger groups of subscribers' lines than other of said switches.
14. The method of maintaining a prescribed order of use of the finder switches of a graded multiple finder system which consists: of connecting the finders to the banks of a homing type distributor in said prescribed order; of starting said distributor 125
15. In a telephone system, a calling line, a plurality of finder switches having access to said line, other finder switches, a plurality 130

from its home position responsive to the initiation of a call in search of the first idle finder connected to its banks; and of returning said distributor to its home position immediately after a finder has been operated into connection with a calling line.

15. In a telephone system, a group of lines, a group of finders having access to said lines, a distributor switch having a normal position, means responsive to simultaneous calls initiated by a plurality of said lines for starting said distributor to select a finder to operate it into connection with one of said calling lines and for reoperating said distributor to 10 select and operate another finder switch into connection with another one of said calling lines, and means responsive to the establishment of a connection with the last of said calling lines for returning said distributor to its 15 normal position.

16. In a telephone system, a group of lines, a group of finder switches having access to said lines, a distributor switch having a normal position, means responsive to the initiation of a call on one of said lines for operating said distributor out of its normal position to 25 select and operate a finder into connection with said calling line, and means responsive to the establishment of said connection for 30 returning said distributor to its normal position.

17. In a telephone system, a group of lines, a group of finder switches having access to said lines, a distributor switch having a normal position, a start relay energized responsive to the initiation of a call on one of said lines and deenergized when a finder connects with that line, means responsive to the energization of said start relay for operating said distributor out of its normal position to select 40 and operate a finder into connection with the calling line, and means controlled by the deenergization of said start relay for returning said distributor to its normal position.

45. 18. In a telephone system in which a homing type distributor is started from normal responsive to the initiation of a call on a line to select and control a finder, to find that line and then release from the finder, a return to 50 normal circuit and a finder selecting circuit in said distributor, a relay energized upon the initiation of a call to open said former and to close said latter circuit, a trunk line outgoing from said finder, a relay in the finder 55 operated when the calling line is found to connect that line to said trunk, means responsive to a successful operation of said finder relay for restoring said first relay and responsive to an unsuccessful operation of said 60 finder relay for maintaining said first relay energized, and means in said distributor operated over said finder selecting circuit after said finder relay has been operated for selecting another finder for operating it into connection with said calling line.

19. In a telephone system, a subscriber's line, a plurality of finders having access to said lines, trunks outgoing from said finders, a distributor having a normal position, a return to normal circuit in said distributor, 70 means responsive to the initiation of a call on one of said lines for opening said return to normal circuit and for starting said distributor out of its normal position in search of an idle finder, means in said distributor responsive to the finding of an idle finder for seizing and starting that finder in search of said calling line, means in said finder for establishing a connection between said line and trunk, means in said distributor responsive to the finder finding said line for operating said finder connecting means and for disassociating said distributor from said finder and for closing said return to normal circuit to return said distributor to normal. 85

20. In a telephone system, subscribers' lines divided into a plurality of groups, finder switches having access to said lines, said finders being arranged in groups corresponding to said line groups, a plurality of trunks outgoing from said finders, direct connections between said finders and trunks, the sum of the numbers of trunks available to said individual line groups is greater than the number of said outgoing trunks. 90

21. In a finder switch system in which some finder switches are assigned to the individual use of a group of lines and other finders assigned to different groups of lines are connected in multiple with each other, a finder allotter, means responsive to the initiation of a call by one of said lines for starting said allotter in search of an idle finder, and means for causing said allotter to select a finder assigned to the individual use of the line group 100 containing the calling line if such a finder is idle. 105

22. In a telephone system in which a homing type distributor is started from normal responsive to the initiation of a call on a line 110 to select and control a finder to find that line and then release from the finder, a return to normal circuit and a finder selector circuit in said distributor, and a relay energized upon the initiation of a call to open said former 115 and to close said latter circuit.

In witness whereof, I hereunto subscribe my name this 28th day of April, 1925.

WILLIAM AITKEN.
